Primary Examiner — Marianne Pandozzi(74) *Attorney, Agent, or Firm* — Banner & Witcoff, Ltd.(57) **CLAIM**

The ornamental design for a bottle, as shown and described.

DESCRIPTION

FIG. 1 is a top, front perspective view of a bottle showing a first embodiment of our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a bottom, front perspective view thereof;

FIG. 9 is a top, front perspective view of a bottle showing a second embodiment of our new design; and,

FIG. 10 is an exploded view thereof.

The broken lines showing the remainder of the bottle are for environmental purposes only and form no part of the claimed design.

1 Claim, 7 Drawing Sheets(56)
